US00D558754S

(12) **United States Design Patent** (10) **Patent No.:** **US D558,754 S**
Takemasa et al. (45) **Date of Patent:** **** Jan. 1, 2008**

(54) **PERSONAL COMPUTER**

(75) Inventors: **Hirofumi Takemasa**, Kadoma (JP);
Miki Kobayashi, Kadoma (JP)

(73) Assignee: **Matsushita Electric Industrial Co., Ltd.**, Osaka (JP)

(**) Term: **14 Years**

(21) Appl. No.: **29/266,539**

(22) Filed: **Sep. 22, 2006**

(30) **Foreign Application Priority Data**

Mar. 27, 2006 (JP) 2006-007527

(51) **LOC (8) Cl.** **14-02**

(52) **U.S. Cl.** **D14/328**

(58) **Field of Classification Search** D14/315-328,
D14/308; D18/1, 2, 7, 11; 235/145 A, 145 R;
